(74) Attorney, Agent, or Firm — MIP LEGAL, LTD.; Bryce D. Miracle, Esq.

(57) **CLAIM**

The ornamental design for a home exterior, substantially as shown and described.

DESCRIPTION

FIG. 1 is a front, left perspective view of the home exterior showing the new design;

FIG. 2 is front, right perspective view thereof;

FIG. 3 is a top plan view thereof;

FIG. 4 is a left side elevation view thereof;

FIG. 5 is a right side elevation view thereof;

FIG. 6 is a front elevation view thereof;

FIG. 7 is a rear elevation view thereof; and,

FIG. 8 is a front, left side perspective view thereof.

The dashed lines depict surface details that form no part of the claimed design.

1 Claim, 8 Drawing Sheets(56)
